UNITED STATES PATENT OFFICE

118,310

DESIGN FOR A SMOKER'S ASHTRAY OR SIMILAR ARTICLE

William C. Panzer, Chicago, Ill., assignor to Russakov Can Company, Chicago, Ill., a corporation of Illinois

Application May 20, 1939, Serial No. 85,107

Term of patent 7 years

To all whom it may concern:

Be it known that I, William C. Panzer, a citizen of the United States, residing in Chicago, Cook County, Illinois, have invented a new, original, and ornamental Design for a Smoker's Ashtray or Similar Article, of which the following is a specification, reference being had to the accompanying drawing forming a part thereof.

I claim:

The ornamental design for a smoker's ashtray or similar article, substantially as shown.

WILLIAM C. PANZER.
